UNITED STATES PATENT OFFICE.

PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

METALLIC CAR END.

1,208,897.

Specification of Letters Patent. Patented Dec. 19, 1916.

Application filed March 8, 1915. Serial No. 13,001.

To all whom it may concern:

Be it known that I, PAUL M. BEARD, a citizen of the United States, residing at the city of St. Louis, State of Missouri, have 5 invented a certain new and useful Improvement in Metallic Car Ends, of which the following is a full, clear, and exact description, such as will enable others skilled in the art to which it appertains to make and use 10 the same, reference being had to the accompanying drawings, forming part of this specification.

My invention relates generally to railway car structures, and pertains specifically to 15 certain improvements in box car ends which may be employed either as a portion of the original car structure, or may be utilized as a repair part to replace ends which have been broken or damaged in service.

20 My improved car end is designed as a unitary structure having the various parts formed with particular reference to one another so as to secure maximum efficiency, and possessed of features which enable it to 25 coöperate effectively with other portions of the car structure to provide a very strong and stable construction.

Heretofore it has been the practice to 30 form car ends of a plurality of sections of sheet metal which are secured together in divers fashions, and which are formed with variously disposed stiffening ribs or corrugations. This portion of the car structure is subjected in service to a variety of shocks 35 and stresses resulting from various flexing and swaying movements in the car structure, impacts and pressures from the lading of the car when the same is shifted in transportation, and various other shocks and impacts arising from vibration, collisions and the like.

Among the purposes of my invention are, 40 the provision of an end structure which may be easily and cheaply manufactured and installed, which may be repaired with a minimum of waste, and which is designed particularly to resist the various destructive stresses to which the structure is subjected.

50 Other objects of my invention will be obvious or pointed out hereinafter.

As illustrated in the accompanying drawings, Figure 1 represents a front elevational view of one form of my improved car end; 55 Fig. 2, a vertical section taken substantially

on line 2—2 of Fig. 1; Fig. 3 a fragmentary side view; Fig. 4 a detail illustrating a fragmentary front view of a modified form; and Fig. 5 a fragmentary detail illustrating a vertical section of the same taken substantially on line 5—5 of Fig. 4. Fig. 6 is a fragmentary vertical section of a second modified form.

Referring to the drawings in detail, it will be understood that 1 represents an 65 upper section of suitable sheet metal, and 2 a lower section. These sections have their edges turned to provide suitable attaching flanges 4, and are formed with duplicate stampings consisting of transverse ribs or 70 corrugations 5 and longitudinal ribs or corrugations 6. Inasmuch as the ribs or corrugations of section 1 are duplicates of the ribs or corrugations of section 2, said ribs or corrugations may be formed in both sec- 75 tions by the same dies.

As is obvious from the illustration, the longitudinal corrugations 6 are disposed adjacent the meeting edges of the sections 1 and 2, and the transverse corrugations 5 extend 80 at substantially right angles to the longitudinal corrugations 6. The margin of section 1 is overlapped upon the margin of section 2 to provide a joint which will act as a water-shed to prevent the ingress of water 85 or dust. At the inner side of the sections, a tie plate 7 is disposed so as to overlap the longitudinal corrugations 6, and is secured to these sections by the lines of rivets or suitable fastenings 8 disposed in the sec- 90 tions at the inward sides of the longitudinal corrugations 6. The marginal portions of the sections are offset, as shown, to accommodate the tie plate and permit its inner face to lie in the plane of the inner surface 95 of the sections. A third line of suitable fastenings 9 is employed to secure the overlapped margins of sections 1 and 2 together and to the tie plate 7. Tie plate 7 is continuous the full length of the sections, and has its extremities turned to provide the attaching plates 7^a which may be of any form or length desired or necessary to enable their being attached to suitable portions of the car body to firmly anchor the 100 end structure. This construction provides a particularly strong joint between the sections. In case of the shifting of the car lading such as would subject the end to internally applied stresses, tie plate 7, to- 105

110

gether with the overlapped margin, forms a compression member and the corrugations 6 a tension member, which members co-operate to resist the internally applied stresses. The tie plate is effective in this manner not only horizontally, but also in a vertical direction, and effectively resists any tendency of the sections to be sprung out along the line on which they are joined.

5 10 This disposal of the tie plate to act as a compression member relative to internally applied stresses, takes the stresses off of the rivet heads, as the tendency of movement of the sections relative to the tie plate will be

15 such as to place the rivets in shear. This is due to the fact, of course, that the portions of the sections adjacent to the corrugations 6 function as a tension member relative to the tie plate 7, and hence there

20 will be a relative sliding tendency between the tie plate and the portions of the sections affixed thereto.

The provision of the corrugations 6 adjacent the edges of both sections 1 and 2 is very effective in preventing the rivets being torn out by local impacts from either within or without the car, as these corrugations strengthen the edges locally by transmitting stresses received thereat across the entire

25 30 structure. This prevents either of the sections being bent at a local area and the rivets torn out.

In the modified form illustrated in Figs. 4 and 5, it will be seen that the corrugations 35 40 extend approximately to the corrugations 6, crossing both the margins of the tie plate 7 and the lines of fastenings 8. This gives added strength to the construction which resists any tendency of the sections to bend on the lines of fastenings 8.

The tie plate 7, in addition to the functions indicated above, has the further effect of preventing the corrugations 6 being flattened out or having their cross-sectional 45 50 contour distorted by stresses received by the sections, as it is secured to the sections at both sides of the corrugations 6, and tends to hold the uncorrugated portions of the sections in their proper plane. The transverse ribs 5 of the respective sections co-operate with their associated longitudinal ribs 6 to strengthen the structure by stiffening it vertically to support vertical loads, the transverse ribs giving the necessary vertical 55 60 stiffening, and the longitudinal ribs operating to hold the vertical ribs in the line of thrust and prevent the lateral bulging or flattening out of the vertical ribs. The provision of a longitudinal rib 6 in each of the sections and extending from corner post to corner post, not only gives the structure added stability, but permits the depth of the transverse ribs being somewhat decreased, thus enabling the hand brake shaft or other 65 car fittings being positioned close to the end.

I am aware that the device is susceptible of changes and modifications not herein illustrated but within the intended scope of my invention. For example: In Fig. 6, I have shown a second modified form in 70 which the second section 2^a is very narrow, being disposed intermediate the first section 1^a and a third section 3^a. This arrangement gives three longitudinal box girder members, formed by the corrugations in the respective sections and the tie plate 7, which in this form spans all three corrugations and is secured to all three sections.

What I claim is:

1. In a car end, a pair of sheet metal sections having their meeting edges overlapped and secured together, each of said sections being provided adjacent its overlapped edge with a longitudinal corrugation extending substantially its entire length, and the said sections being connected by a tie plate co-operating with the said corrugated portions to form box girder members.

2. In a car end, a pair of sheet metal sections provided adjacent their meeting edges 90 with longitudinal corrugations extending substantially from margin to margin of the sections, said sections having their meeting edges secured together, and a tie plate extending continuously from margin to margin of the sections and overlapping said corrugations and secured to the respective sections by lines of fastenings on both sides of the respective corrugations.

3. In a car end, a pair of sheet metal sections provided at their opposite margins with means for attachment to car framing members and provided adjacent their meeting edges with longitudinal corrugations extending approximately to their opposite 105 margins, said sections having their meeting edges overlapped and secured together, and a tie plate overlapping said corrugations and secured to said sections at opposite sides of said corrugations, said tie plate being 110 provided at its opposite ends with means whereby it may be affixed to a car.

4. In a car end, a pair of sheet metal sections having their meeting edges secured together and each provided with an outwardly 115 pressed corrugation adjacent said edges, and a tie plate overlapping the reentrant sides of said corrugations and secured to the sections, said tie plate extending continuously between opposite margins of the sections.

5. In a car end, a pair of sheet metal sections having their meeting edges secured together and provided adjacent said meeting edges with outwardly pressed corrugations forming truss members extending substantially from margin to margin of the sections, and a tie plate secured to said sections on the inner side thereof, and forming a truss member co-operating with said corrugations.

6. In a car wall structure, a pair of sheet metal sections having their meeting edges secured together and provided adjacent thereto with longitudinal corrugations, and a tie plate secured to said sections at opposite sides of said corrugations and coöperating therewith to form box girders in the wall structure. 40
- 5 7. In a car end, a pair of sheet metal sections having their meeting edges secured together and provided adjacent thereto with longitudinal corrugations, and a tie plate secured to said sections and coöperating with said corrugations to provide a pair of juxtaposed box girder members extending intermediate opposite margins of the end structure. 45
- 10 8. In a car end, a pair of sheet metal sections having their meeting edges secured together and provided adjacent thereto with longitudinal corrugations and offset portions and a tie plate disposed in the offset portions and secured to the respective sections across their line of jointure. 50
- 15 9. In a car end, a pair of sheet metal sections having their meeting edges secured together and provided adjacent thereto with longitudinal corrugations, said sections being further provided with corrugations extending in directions transverse of said longitudinal corrugations, and a tie plate overlapping said longitudinal corrugations and the near extremities of said transverse corrugations and secured to the respective sections intermediate the extremities of the transverse corrugations thereon. 55
- 20 10. In a car end, a pair of sheet metal sections, a tie plate overlapping the meeting edges thereof and secured to the respective sections, each of said sections being provided with a longitudinal corrugation disposed intermediate the edges of said tie plate, and said sections being provided with transverse corrugations terminating intermediate the edges of said tie plate. 60
- 25 11. In a car end, a pair of sheet metal sections having their meeting edges secured together, one of said sections being provided with a longitudinal corrugation extending substantially parallel to said meeting edges, 50 and a tie plate secured to both of said sections along the meeting edges and coöperating with said corrugation to form a box girder extending longitudinally of the sections adjacent their conjoined edges. 65
- 30 12. In a car end, a pair of sheet metal sections disposed together to form a wall and having their meeting edges conjoined, each of said sections being provided with a corrugation extending longitudinally thereof along the line of jointure, and a tie plate disposed across the reentrant sides of said corrugations and secured to the sections along the line of jointure intermediate the corrugations and along the remote sides of the corrugations, and coöperating therewith to provide a reinforcing member extending longitudinally of the sections. 70
- 35 In testimony whereof I hereunto affix my signature in the presence of two witnesses, 70 this 27th day of February, 1915.
